UNITED STATES PATENT OFFICE.

JEAN L. SCHIMMELFENG, OF WARREN, PENNSYLVANIA.

METHOD OF ASSEMBLING COMMUTATORS.

1,214,960.

Specification of Letters Patent. Patented Feb. 6, 1917.

Application filed March 1, 1916. Serial No. 81,594.

To all whom it may concern:

Be it known that I, JEAN L. SCHIMMELFENG, a citizen of the United States, residing at Warren, in the county of Warren and State of Pennsylvania, have invented new and useful Improvements in Methods of Assembling Commutators, of which the following is a specification.

This invention relates to methods of assembling commutators and consists in certain improvements therein as will be hereinafter fully described and pointed out in the claims.

Commutator bars are ordinarily formed with dovetailed shanks forming bevels at the ends and these are engaged by rings having corresponding bevels, the rings being connected by a shaft or shell so as to hold the assembled bars and their insulating material together. It is desirable to draw the bars radially and to secure them under compression so that there is a clamping action circumferentially not only holding the bars in place but the insulating material. Devices for carrying out my process are illustrated in the accompanying drawings as follows:—

Figure 1 shows a portion of a press with a commutator in process of assembling in section.

Fig. 2 is a plan view of an assembled commutator.

Fig. 3 is a section on the axis of the commutator.

1 marks the commutator bars. These have the dovetail shaped shanks 2 forming the bevels at the ends. The ring 3 having the bevel 4 corresponding to the bevel on the shank 2 is arranged at one end. This has the shaft or shell 5 extending axially through the commutator forming an opening through which the shaft (not shown) on which the commutator is usually mounted extends. A ring 6 is arranged at the opposite end of the commutator from the ring 3 and it has the beveled shoulder 7 corresponding to the beveled end of the shank 2. The ring 3 has a tapered opening 6^a extending through it and the end of the shell or shaft 5 extends through this opening.

Insulating strips 8 are arranged between the commutator bars and insulating strips 9 are arranged between the rings 3 and 6 and the commutator bars.

In assembling the commutator, the bars are arranged as shown in Fig. 1 with the insulating strips between the bars and the in-

sulating strips 9 in place. The rings 3 and 6 are engaging the beveled ends of the shanks 2. The end of the shaft or shell 5 extends through the opening 6^a. The commutator so far assembled is placed on a die 11 of the press, the die having a centering extension 12 which extends into the shell 5.

The die 13 has an extension 14 which is adapted to pass into the shell 5, a turning shoulder 15 being arranged on the upper end of the extension 14. A cross head 16 is secured at the upper end of the die 13 and it is connected to a pressure head 17 by bolts 18, the bolts being screwed into the head 17 and extending through perforations 19 in the cross head 16. A spring 20 is arranged between the cross head 16 and the pressure head 17. The pressure head 17 has a ring 17^a adapted to engage the ring 6 as the die is forced downwardly by the press. The die is carried by the reciprocating plunger 21 mounted in an ordinary press.

Carrying out the process the plunger 21 is forced downwardly carrying with it the die. The extension 14 enters the end of the shell thus holding it fully expanded. The ring 17^a of the pressure head 17 reaches the ring 6 and with a further movement of the plunger exerts axial pressure on the ring 6 which pressure operating through the beveled shoulders 4 and 7 in opposition to the beveled shoulders on the ends of the dovetailed shanks 2 draw the commutator bars inwardly and this inward movement of the commutator bars brings them into a smaller circumference and consequently clamps them circumferentially, firmly securing them together and firmly securing the insulating strips in place. With the continued movement of the die 13, the pressure from the pressure head on the rings is continued, the spring 20 yielding and allowing the continued movement of the die. When the forming shoulder 15 reaches the end of the shell 5 it forces the end of the shell 5 over forming a head 10 (see Fig. 3) which completes the connection between the rings. It will be noted that as the shell 5 is headed over the rings 3 and 6 are under axial pressure so that the heading over is done without the pressure being slackened in the least on the rings. This assures a positive clamping of the bars through the action of the rings 3 and 6.

What I claim as new is:—

1. The method of assembling commutators

comprising commutator bars having dove-tailed shanks with beveled ends; interposed insulating strips; tapered end rings on the beveled surfaces of the dove-tailed shanks; 5 and interposed insulating material between the rings and the bars which consists in exerting axial pressure on the rings to draw the bars inwardly and compress them and the interposed insulation circumferentially 10 and securing the rings together while under pressure.

2. The method of assembling commutators comprising commutator bars having dove-tailed shanks with beveled ends; interposed 15 insulating strips; tapered end rings on the

beveled surfaces of the dove-tailed shanks; interposed insulating material between the rings and the bars; and a connecting shaft 20 between the rings, one end of the shaft extending through one of the rings, which consists in exerting axial pressure on the rings to draw the bars inwardly and compress them and the interposed insulating material circumferentially and heading over the shaft while the rings are subjected to the axial 25 pressure.

In testimony whereof I have hereunto set my hand.

JEAN L. SCHIMMELFENG.
